WIRE MESH PANEL FOR POULTRY CAGES

Gerald L. Kitson, 9709 Belding Road,
Rockford, Mich. 49341

Filed May 14, 1971, Ser. No. 143,733

Term of patent 14 years

Int. Cl. D30—02

U.S. Cl. D30—2

FIG. 1 is a front elevation of the wire mesh panel for poultry cages embodying my new design.

FIG. 2 is a top plan view of the wire mesh panel for poultry cages shown in FIG. 1.

FIGS. 3 and 4 are end and bottom plan views, respectively, of the wire mesh for poultry cages shown in FIG. 1 and FIG. 2.

I claim:

The ornamental design for a wire mesh panel for poultry cages, as shown.
